WALL PANELING

Frederich Richard Ashby, Carmel, N.Y., and Donald F. Luebs, Vienna, Va., assignors to U.S. Plywood-Champion Papers Inc., New York, N.Y.

Filed Apr. 30, 1970, Ser. No. 22,726

Term of patent 14 years

Int. Cl. D25—01
U.S. Cl. D13—1

FIG. 1

FIG. 2

FIG. 3

FIG. 4

FIG. 5

FIG. 6

FIG. 1 is a top plan view of a section of a large board or panel, while

FIG. 2 is an end view of FIG. 1 showing the tongue and groove.

FIG. 3 is a plan view of a slightly different modification of the design, while

FIG. 4 is an end view thereof.

FIG. 5 is a plan view of a still different variation of the basic invention, while

FIG. 6 is an end view thereof.

We claim:

The ornamental design for a wall paneling, as shown and described.
